UNITED STATES PATENT OFFICE.

WILLIAM H. SAUVAGE, OF FLUSHING, NEW YORK, ASSIGNOR TO ATLANTIC HAND BRAKE CORPORATION, OF BUFFALO, NEW YORK.

HAND-BRAKE.

1,330,140.

Specification of Letters Patent. Patented Feb. 10, 1920.

Application filed May 19, 1919. Serial No. 298,199.

To all whom it may concern:

Be it known that I, WILLIAM H. SAUVAGE, a citizen of the United States of America, residing at Flushing, Long Island, in the 5 county of Queens and State of New York, have invented certain new and useful Improvements in Hand-Brakes, of which the following is a specification.

This invention relates to improvements in 10 hand-brakes and more particularly to hand-brakes particularly adapted for use on railway vehicles such as freight cars, passenger cars and suburban cars. As is well known, the transportation laws require vehicles to 15 be equipped with hand-brakes as well as air-brakes owing to the failure of the latter to operate in certain emergencies.

It is, therefore, one of the objects of the 20 present invention to provide a simple and practical hand-brake which may be easily and quickly applied to railway vehicles now in use without materially changing the foundation brake rigging.

A further object is to provide a brake 25 mechanism of the above character having relatively few parts which may be inexpensively manufactured and assembled.

A further object is to provide a brake mechanism of the last above mentioned character adapted to quickly take up the slack 30 and apply the brakes with great pressure.

A further object is to provide a brake mechanism of the last above mentioned character which will permit the release of the 35 brakes easily and quickly when desired after they have been applied. A further object is to provide a safety feature whereby excessive braking power is prevented.

These and other objects will appear more 40 clear from the description hereinafter set forth. In order that the present invention may be more fully understood, drawings are attached and form a part of the specification, illustrating two of the various possible embodiments of the present invention, in which similar reference characters denote corresponding parts.

In these drawings Figure 1 is a front elevational view, partly in section, showing 45 such portions of the mechanism as are necessary to fully understand the present invention,

Fig. 2 is a side elevational view of the part shown in Fig. 1 with portions broken away or omitted for the sake of clearness. 55

Fig. 3 is a transverse sectional view taken substantially on the line 3—3 of Fig. 1.

Fig. 4 is a view similar to Fig. 1, showing a slight modification.

Figs. 5 and 6 are views taken on substantially the lines 5—5, 6—6, Fig. 4.

Referring now to the drawings in detail, and particularly Fig. 1, 5 indicates a rectangular casing of metal or other suitable material provided with perforated ears 6 65 whereby the same may be conveniently attached to the dashboard of a suburban car or the end wall of a freight car, for example. This box is provided with a removable cover 7, held in place by a cap screw 70 8, in order that the parts may be easily assembled or lubricated, or worn parts removed.

Within this casing and at one side thereof 75 is provided a short shaft 10, the major portion of which is provided with threads 11 while the lower end 12 is mounted in a suitable perforation or bearing in the bottom of the casing. The upper part of the shaft 80 is provided with a perforated hand-wheel 13 of any desired type but preferably of sheet metal and provided only with hand grip holes whereby the insertion of a bar is prevented, for it will be seen that the mechanism hereinafter described is of such high 85 gear that to insert a bar in the wheel to obtain greater leverage would probably exert such a severe strain on the foundation brake rigging as to cause excessive braking power.

At the opposite side of the casing is 90 mounted a second shaft 14, also provided with rack teeth 15 throughout the major portion of its length and terminating at its lower end in a bearing 19. Both these ends 12 and 14 are provided with washers or 95 the like 16 and pins 17 to hold the same in place. The upper part of the shaft 14 is provided with a handle 18 which may be turned between pins 20 and 21, Fig. 2, for the purpose of bringing a longitudinal slot 100 23 into and out of mesh with a centrally disposed gear 24. This gear is provided with a central shaft 25 carrying a stirrup or clevis 26, the lower end of which is con-

nected with a link 27, Fig. 2, at the end of a chain or pull rod connecting the operating mechanism with the foundation brake rigging. It will be noted that the casing 5 is provided with grooves 27 at its front and rear sides as shown more clearly in Fig. 3 for permitting this gear 24 to be positively guided in its up and down movements, and to stop the gear from falling to the bottom 10 of the casing.

With this description of the construction in mind, a brief statement of the operation is as follows:—

When it is desired to apply the brakes, 15 the hand-wheel 13 is rotated in a direction to cause the gear 24 to move relatively upward in its guided channels, as shown by the dotted line position in Fig. 1. The teeth of the gear 24 will mesh with the worm on 20 the shaft 14 which in this position acts as a fixed or rotatable rack, thus permitting the load carried by the gear 24 to be evenly distributed between the two shafts. In this 25 manner a great braking power may be exerted upon the foundation brake rigging through this mechanism. After the brakes are applied the handle 18 is swung from its position in engagement with the lug 21 into engagement with the lug 20. This causes 30 the slot 23 to register with the teeth of the gear 24 which gear immediately drops to the bottom position thereby releasing the application of the brakes quickly if desired.

The mechanism shown in Fig. 4 is substantially the same as that already described 35 with the exception that the member 30 corresponding to the shaft 14 is preferably held in fixed position by means of a set screw 31. Also, shaft 32, corresponding to the shaft 40 10, is held in raised position by means of a spring 33, seated in a suitable housing 34, under adjustable tension, by means of the screw cap 35. This spring 33 engages a washer 36 keyed or pinned at 37 to the 45 shaft 32.

At one side of the casing 5 is an opening in which is mounted a pin 38, held in the position shown by means of a cotter pin 40. The inner end of this pin 38 is adapted to 50 55 coact with the end 41 of the threaded shaft 32 when, by reason of excessive pull on the gear 24, the shaft 32 will be moved downwardly against the resistance of the spring 33. In this manner excessive braking power, through the high power gear mechanism shown, is positively prevented from being transmitted to the brake rigging.

The operation of this mechanism is substantially the same as that above described, 60 and it is believed that further description is unnecessary.

From the above description it will be seen that the present invention provides a simple and practical and powerful hand-brake

mechanism adapted to accomplish, among 65 others, all the objects and aims herein set forth.

What I claim is:

1. In a hand brake mechanism, in combination a member adapted to be connected 70 with the brake rigging, a normally stationary member adapted to be engaged by a rotary member, and a member lying parallel to said stationary member and coacting with the said rotary member to move said rotary 75 member along said stationary member to apply the brakes.

2. In a hand-brake mechanism, in combination, a stationary member having a rack portion, a rotary pinion connected with the 80 foundation brake rigging adapted to move along said rack portion, and an actuating member provided with a worm for rotating said rotary pinion whereby it moves equally along said rack portion and said actuating 85 member to apply the brakes.

3. In a hand-brake mechanism, in combination, a housing provided with guides on its opposite inner surfaces, a pinion adapted 90 to move along said guides and connected with the foundation brake rigging, a rack member at one side with which said pinion is adapted to mesh and an actuating worm engaging the opposite side of said pinion whereby as said worm is rotated, said pinion 95 will travel along said worm and rack portion.

4. In a hand-brake mechanism, in combination, a housing provided with guides on its opposite inner surfaces, a pinion adapted 100 to move along said guides and connected with the foundation brake rigging, a rack member at one side with which said pinion is adapted to mesh, an actuating worm engaging the opposite side of said pinion 105 whereby as said worm is rotated, said pinion will travel along said worm and rack portion, and means for throwing said pinion and rack portion out of mesh whereby the 110 brakes may be released.

5. In a hand-brake mechanism, in combination, a housing, a pinion mounted within said housing and adapted to move longitudinally therein, means for connecting said pinion with the foundation brake rigging, 11 a mutilated worm at one side of said casing normally in mesh with said pinion, an actuating worm at the opposite side of said casing in mesh with said pinion, and means for actuating said worm whereby said pinion will be caused to travel along said worms 12 to apply the brakes.

6. In a hand-brake mechanism, in combination, a housing, a pinion mounted within said housing and adapted to move longitudinally therein, means for connecting said pinion with the foundation brake rigging, a mutilated worm at one side of said casing 12

- normally in mesh with said pinion, an actuating worm at the opposite side of said casing in mesh with said pinion, means for actuating said worm whereby said pinion 5 will be caused to travel along said worms to apply the brakes, and means adapted to rotate said mutilated worm to throw the same out of mesh with said pinion.
7. In a hand-brake mechanism, in combination, a housing provided with worms at its opposite sides, a hand-wheel for operating one of said worms, and a gear interposed between the worms adapted to travel therewith when said hand-wheel is turned 10 to equally distribute the load therebetween.
8. In a hand-brake mechanism, in combination, a housing provided with worms at its opposite sides, means for operating one of said worms, and a gear interposed between the worms adapted to travel therewith when said means is operated, one of said worms being provided with a longitudinal slot, and means for turning 15 said worm whereby said slot is brought into alignment with said pinion to permit the pinion to drop thereby to release the brakes.
9. In a hand-brake mechanism, in combination, a casing; worm shafts at opposite 20 sides of said casing, a pinion therebetween, means connecting said pinion with the foundation brake rigging, and a spokeless hand-wheel connected with one of said worm shafts whereby the worm may be rotated to 25 cause said pinion to travel equally along both of said worm shafts.
10. In a hand-brake mechanism, in combination, a casing, worm shafts at opposite sides of said casing, a pinion therebetween, 30 means connecting said pinion with the foundation brake rigging, and a hand-wheel connected with one of said worm shafts whereby the worm may be rotated to cause 35 said pinion to travel along both of said worm shafts, one of said worm shafts being provided with a slot adapted to be thrown into alignment with said pinion to permit the pinion to move to release the brakes.
11. In a brake mechanism, in combination, a rack, a rotatable gear adaptable to move therewith, and a second gear rotatable to 40 coact with said first mentioned gear, and adapted to move said first mentioned gear bodily along said rack to apply the brakes.
12. In a brake mechanism, in combination, a rack, a rotatable gear adaptable to move therewith and a second gear rotatable to coact with said first mentioned gear, and adapted to move said first mentioned gear bodily along said rack to apply the brakes, 45 and said second mentioned rotatable gear being in the form of a worm and lying substantially parallel to said rack.
13. In a brake mechanism, in combination, a rack, a rotatable member adapted to move therewith and move bodily therewith to apply the brakes, and a rotary self-locking actuating member adapted to move said rotatable member.
14. In a brake mechanism, in combination, a rack, a rotatable member adapted to move therewith and move bodily therewith to apply the brakes, and a rotary self-locking actuating member adapted to move said rotatable member, said last mentioned member being in the form of a worm and lying substantially parallel to said rack.
15. In a hand-brake mechanism, in combination, a rotatable member adapted to be connected with the foundation brake rigging, a stationary member in engagement with said rotary member, an actuating member adapted to move said rotary member along said stationary member and said actuating member to apply the brakes, and means associated with one of said parts adapted to prevent excessive braking power from being transmitted to the foundation brake rigging.
16. In a hand-brake mechanism, in combination, a housing, a pinion mounted within said housing and adapted to move longitudinally therein, means for connecting said pinion with the foundation brake rigging, a mutilated worm at one side of said casing 5 normally in mesh with said pinion, an actuating worm at the opposite side of said casing in mesh with said pinion, means for actuating said worm whereby said pinion will be caused to travel along said worms to apply the brakes, and means adapted to prevent excessive braking power being transmitted to the foundation brake rigging.
17. In a hand-brake mechanism, in combination, a casing adapted to be secured to the wall of a car, two worms within said casing and at opposite sides thereof, a pinion adapted to mesh with the teeth of said worms and to be moved therewith when one of said worms is actuated, and means adapted to prevent excessive braking power being transmitted to the foundation brake rigging.
18. In a hand-brake mechanism, in combination, a casing adapted to be secured to the wall of a car, two worms within said casing and at opposite sides thereof, a pinion adapted to mesh with the teeth of said worms and to be moved therewith when one of said worms is actuated, and means adapted to prevent excessive braking power being transmitted to the foundation brake rigging, said means including a spring yieldingly supporting the actuated worm and adapted to yield when excessive load is applied thereto.
19. In a hand-brake mechanism, in combination, a casing adapted to be secured to the wall of a car, two worms within said cas-

ing and at opposite sides thereof, a pinion adapted to mesh with the teeth of said worms and to be moved therealong when one of said worms is actuated, means adapted to prevent excessive braking power being transmitted to the foundation brake rigging, said means including a spring yieldingly supporting the actuated worm and adapted to yield when excessive load is applied thereto, and a stop associated with the

casing adapted to engage with the worm to prevent further turning thereof when excessive load is supported thereby.

In testimony whereof I affix my signature in the presence of two witnesses.

WILLIAM H. SAUVAGE.
